[57] CLAIM

The ornamental design for a computer icon for a computer monitor, as shown and described.

DESCRIPTION

FIG. 1 is a front view of a computer icon for a computer monitor;

FIG. 2 is a second embodiment thereof;

FIG. 3 is a third embodiment thereof; and,

FIG. 4 is a fourth embodiment thereof.

The broken line drawing of a computer monitor in all figure views is for illustrative purposes only and forms no part of the claimed design.
